Specification of Letters Patent. Patented Sept. 14, 1920.

Application filed December 13, 1919. Serial No. 344,606.

To all whom it may concern:

Be it known that we, CHARLES H. PEIRSON and CHARLES H. BUTLER, citizens of the United States, residing in Glenside, Mont. 5 Co., Pennsylvania, and Philadelphia, Pennsylvania, respectively, have invented certain Improvements in Presses, of which the following is a specification.

This invention relates to machines for forming shaped leather washers, packings, and similar articles, and the object of the invention is to provide an improved method and machine whereby the manufacture of the said articles is simplified and the output 15 materially increased while involving less labor.

In the attached drawings:

Figure 1 is a front elevation of the machine;

Fig. 2 is a side elevation of the machine;

Figs. 3, 4, and 5, are horizontal sections taken on the lines *a—a*, *b—b*, and *c—c*, respectively, in Fig. 1;

Fig. 6 is a vertical section of the upper portion of the machine, taken on line *d—d*, Fig. 3; and

Fig. 7 is a vertical section of the lower portion of the machine, taken on the line *e—e*, Fig. 5.

With reference to the drawings, the machine consists of a hydraulic press comprising a pedestal 1, to which is attached a main frame consisting of a lower frame 2, and an upper frame 3, said upper frame being joined to said lower frame by means of upright bolts 4, two upon each side of the press. A vertical cylinder 5 is formed in the main frame 2, and a pipe 6 connects said cylinder with a suitable source of hydraulic power. Located within the cylinder is a ram 7, said ram being attached to a movable platen, 8, which travels between and is guided by said bolts 4, the upward motion being obtained by hydraulic pressure within the cylinder 5, operating against the ram 7, and the downward motion being caused by gravity. Upright bolts 9, one at each side, extend upwardly from said movable platen, 8, and an upper movable platen 0 or carriage, 10, located above the upper frame 3, is mounted upon said bolts 9, and is adapted to slide thereon, the travel of said upper platen relative to said bolts 9,

being limited by the nut 11 upon the upper extremity thereof and the collars 12 attached in suitable manner to said bolts 9 intermediate the ends thereof. Extending above the upper platen 8, is a hollow cylinder member 13, having located therein an upper ram 14, said ram being extended and the lower portion thereof passing downwardly through a central opening 15 formed in the upper platen 10 and into a well, 16, formed in the upper frame 3, to which it is secured in any suitable manner, in the present instance by a set screw, 17. A pipe 18 establishes connection between the cylinder 13 and a suitable source of hydraulic power.

The operation of the machine in so far as described, is similar to that of any hydraulic press of this type. Hydraulic pressure may be applied to the ram 7 within the cylinder 5 to raise the platen 8 and force it against the bottom of the upper frame 3, while pressure applied to the ram 14 within the cylinder 13 will force the upper platen 10 and the lower platen 8 to which it is attached downward.

Resting upon the lower platen 8 and hinged to one of the bolts 4 by means of an extending lug 19 through which the said bolt passes, is a bed plate 20, said bed plate being adapted to be swung outwardly upon the lug 19 by means of a handle 21, thereby giving free access over the entire surface of said bed plate and consequently to anything thereon. Borne upon the said bed-plate, and properly positioned thereon by means of pins 22, which extend into holes 23 in the bed plate, is a set of male dies, 24, 25 and 26—the bed plate in the present case being adapted to take three of said dies, the larger one 24 of which only is shown upon the bed plate, these dies being held concentrically positioned and spaced upon the plate by means of the said pins 22, three of which are carried by each die, the said pins fitting into holes 23 made to correspond therewith in the bed plate.

Secured to the nether surface, of the upper frame by means of bolts 27, or in any manner which may be found suitable, are a set of female dies corresponding in number and size with the male dies upon the bed plate 20, and disposed directly opposite thereto, said set of female dies consist-

ing in the present instance of three dies, 28, 29 and 30 corresponding to the male dies 24, 25 and 26 respectively, the male dies 25 and 26 being shown depending from the female dies 29 and 30 in which they are retained by friction due to the leather washer compressed between the male and female dies as will later be more fully explained.

Located within each of the female dies is 10 an ejector ring, 31, 32 and 33, respectively, and secured to each of said ejector rings are four vertical ejector pins 31^a, 32^a and 33^a said pins of each ring being arranged at angles of 90 degrees around the circumference. The pins extend upwardly through holes 31^b, 32^b and 33^b formed in the base of the said dies, and through radial slots 34, 35, 36 and 37 in the upper frame 3. The rings 31, 32 and 33 are adapted to slide 15 within the annular space in the female dies and shoulders 31^c, 32^c and 33^c are formed upon the pins, said shoulders serving in conjunction with the upper surfaces of the female dies to retain the rings within their 20 respective annular spaces.

The upper platen or carriage 10 comprises a body 38, a cam plate 39 and four sets of guides 40 which are secured to the under side of the said body and which support the cam plate 39 within the body 38. The body 38 has secured to each side thereof a lug 41 through which pass the bolts 9, whereby connection is made between the said upper and lower platens. The cam 25 plate 39 is free to rotate around its axis and a handle 42, secured to the said plate and extending outwardly over the edge of the frame, furnishes a means whereby the cam plate may be thus turned. Supported in the slots between each of the sets of guides 40 and adapted to travel back and forth therein is an ejector pin 43, said pins having in the present instance recesses 44 formed in the sides thereof into which the 30 sides of the guides extend, thereby supporting the said pins while permitting movement along the guides. Secured upon the top of each of the pins 43 by means of screws 45 is a roller 46, each of said rollers extending upwardly into one of the four cam obliquely disposed slots 47 in the cam plate 39. It will now be seen that as the cam plate is turned by means of the handle 42, the ejector pins 43 will be forced in or out, 35 as the case may be, between their respective guides 40, this movement being effected by the action of the cam slots 47 upon the roller 46.

In forming the leather washers by means 40 of the machine described a leather blank in the form of a band or belt is employed, instead of the usual disk shaped blank. These blanks are first placed around the outside of the male dies in a vertical position and 45 the upper half thereof which extends above

the upper edge of the die is then pushed inwardly over the top of the die as illustrated in Fig. 1, which shows the leather blank 48 extending around the male die 24, the upper portion of the blank 48 extending above the 70 upper edge of the said die and being bent inwardly over the top edge of the die, said blank 48, being shown in broken lines. In this condition the leather blank and the male die are in readiness to be forced into 75 the female die attached to the upper frame for forming the shaped washer, the finished washer being in the present case of U-shaped cross section, or what is commonly known as a U leather.

The lower platen is now carried upward by hydraulic pressure acting upon the ram 7, and the male die carrying the leather blank enters the corresponding female die upon the upper frame and is forced to the 80 entire depth of said female die, the ejector ring located within said female die together with the pins attached thereto being forced upwardly. The final position assumed by the various elements of the dies is shown in 85 Fig. 6, in which the two smaller male dies 25 and 26 together with the leather blanks are established within the female dies 29 and 30, and also here illustrated is the fact that after the lower platen is lowered away 90 from the upper frame the male dies 25 and 26 remain dependent from the female dies, being held by the pressure created by the compressed leather.

It thus becomes necessary, when the 100 leather has remained a sufficient length of time, under compression, to remove the same together with the male die from the female by force, and this is accomplished by means of the upper platen 10 and the ejector pins 105 carried thereby. This upper platen 10 is carried upward as the lower platen rises by means of the collars 12 upon the bolts 9, the collars abutting the lugs 41 and being so located upon the said bolts that when the 110 lower platen is at the extreme upper position the lower ends of the ejector pins 43 just clear the top of the pins 31^a, 32^a and 33^a, carried by the ejector rings 31, 32 and 33. In this position of the upper platen the ejector pins 43 may be moved to a position directly over any one of the sets of pins 31^a, 32^a or 33^a; and as the pressure in the cylinders 5 is relieved and the lower platen starts to move 115 downwardly, pressure is applied in the cylinder 13 whereby the upper platen is forced downward, and the pins 43 impinging upon the pins 31^a, 32^a and 33^a as the case may be, the ejector ring within the female die is forced downward, with the consequent ejection 120 of the now shaped leather and the male die. It is apparent that the ejection of the male die and the beginning of the downward motion of the lower platen are simultaneous, and as the male die with the shaped leather 125 130

thereon leaves the female die, the pins 22 still extend into their respective holes 23 in the bed plate 20, whereby the dies are held properly positioned thereon.

5 With a machine of this type employing several sets of dies, a continuous action is possible. As a blank is forced into one of the female dies, the finished leather in the adjacent die is removed. In other words, 10 each reciprocation of the lower platen drives a new blank into one of the female dies and removes a shaped leather from one of the others, each leather remaining under compression the length of time required to remove the leathers from the other dies and 15 replace them by new ones, or in the present instance, during two complete reciprocations of the platens.

Referring to Figs. 6 and 7 and considering them together as parts of an assembled machine, the male die 24 together with a shaped leather 50 has just been ejected from the female die, 28, the male dies 25 and 26 being shown depending from the female dies 29 and 30, in which leathers, 51 and 52, are under compression between the two (male and female) dies. The next step in the operation is to remove the finished leather 50 from the die 24 and replace it by a new blank, 30 after which the die and blank are forced up into the female die. While the platens are in the elevated position the pins 43 are moved inwardly in the manner already described so that as the platens return to normal low position, the male die 25, carrying 35 its shaped leather 51, is ejected from the female die 29. The leather 51 is now replaced by a new blank, which is then forced into the female die 29, after which the male die 26 and the shaped leather 52 are forced from the female die 30, a new blank forced 40 into this female die 30, the now shaped leather in the female die 28 ejected and the cycle repeated.

45 The operation of the machine is continuous and cyclical so that the waste of time contingent upon the former method of single shaping is avoided, there being no delay while waiting for the leathers to set. This 50 machine and the use therewith of belt shaped rather than disk shaped blanks materially decreases the time consumed in forming these shaped leathers and simplifies the process to a great degree, the result being 55 that the cost involved in the manufacture of the article is greatly reduced. The machine may be modified in many respects in so far as the details thereof are concerned with no departure from the essential features of the 60 invention, and although this machine has a particular application to the shaping of leather articles it is clear that its use may extend to articles of other material as well.

Having now fully described our invention 65 and having made clear the operation of the

machine and the various steps involved in the method of forming shaped leathers and the like, we claim:

1. In a press, a set of fixed dies and a corresponding set of movable dies, means 70 for carrying said movable dies forward toward their corresponding fixed dies for compressing article therebetween, and backward from said fixed dies after compression is completed, said movable dies being frictionally retained by their respective fixed dies while articles are under compression there between, and means whereby any one of said retained dies is released, together with the article compressed thereby, simultaneously 75 with each backward movement of said carrying means.

2. In a press, a stationary frame, a set of fixed dies secured to said frame, a movable platen, a set of movable and independent 85 dies corresponding to said fixed dies carried by but not secured to said platen, said platen being adapted to reciprocate to carry said movable dies to and from their respective companion fixed dies, means operably connected with said platen for forcing said movable dies toward the fixed dies to compress articles therebetween, said movable dies being frictionally retained with the work between themselves and the fixed dies, and 90 means operating in conjunction with the movable platen for releasing one of said retained dies together with the compressed article simultaneously with each backward movement of said platen. 100

3. In a press, a fixed frame and a platen adapted to travel therein, a set of female dies secured to said frame and a corresponding set of male dies carried by but not secured to said platen, said platen being 105 adapted to reciprocate to carry said movable dies to and from their respective companion fixed dies, means connected with said platen for forcing said male dies and articles to be compressed into their respective 110 female dies, said male dies being frictionally retained in said female dies while said articles are under compression, an ejector carried by each of said female dies, said ejector comprising a movable ring located 115 in the interior of said dies, pins attached to said rings and extending through apertures in the base of said dies, and actuating means for said ejectors comprising a series of reciprocating selector pins adapted to engage 120 the ejector pins of said female dies, means for adjusting said selector pins to engage the ejector pins of any one die desired, and means for advancing said selector pins to engage said ejector pins simultaneously with 125 each backward movement of said platen.

4. In a press, a fixed frame and a platen adapted to travel therein, a set of male dies carried by but not secured to said platen, and a set of female dies corresponding with 130

4
said male dies secured to said frame, means for moving the platen toward the said female dies for forcing the male dies and articles to be compressed into their respective 5 female dies, said platen being returned by gravity to its original position, and said male dies being frictionally retained in their respective female dies while an article is under compression therebetween, ejectors carried 10 by each of the female dies for discharging said retained male dies therefrom together with the compressed articles, and means connected with said platen for actuating said ejectors, said actuating means comprising a carriage, pins carried thereby, means for adjusting said pins for engaging the ejector in any one of said dies, and means for moving said carriage to bring said engaging pins 15 into operation simultaneously with each return movement of the platen.

20 5. In a press, a fixed frame and a platen adapted to travel therein, a set of female dies secured to said frame, and a corresponding set of male dies carried by but not secured to said platen, said platen being adapted to reciprocate for moving said male dies 25

forward toward their corresponding female dies to compress articles therebetween, and backward from said female dies after compression of said articles, said male dies being frictionally retained in their respective female dies while an article is under compression therebetween, an ejector carried by each of said female dies for releasing said retained male dies and compressed articles, 30 means for actuating said ejectors, said actuating means comprising a carriage, radial slots carried thereby, pins mounted and adapted to travel in said slots for engaging said ejectors, a cam plate containing a cam 35 slot for each of said pins, said pins each having an extension projecting into its respective cam slot, means for rotating said cam plate for disposing the pins in their slots to engage any one of said ejectors, and 40 means for moving said carriage to bring said pins into engagement with a chosen ejector simultaneously with each backward movement of said platen.

CHARLES H. PEIRSON.
CHARLES H. BUTLER.
